EX

Nicholas Muller's Design for a Statuette

3841

PATENTED FEB 8 1870

Charles F. Adams
Lewis G. Frankle

Nicholas Muller
Inventor

United States Patent Office.

NICHOLAS MÜLLER, OF NEW YORK, N. Y.

Design No. 3,841, dated February 8, 1870.

DESIGN FOR AN EQUESTRIAN STATUETTE.

The Schedule referred to in these Letters Patent and making part of the same.

To all whom it may concern:

Be it known that I, NICHOLAS MÜLLER, of the city, county, and State of New York, have invented a new and useful Design for an Equestrian Statuette; and I do hereby declare the following is a full and exact description thereof, reference being had to the accompanying photograph forming a part of this specification, giving a perspective view of the design.

This invention relates to a design for an equestrian statuette representing a Mexican herdsman or ranchero in the act of throwing a lasso. The design may be divided into two parts, horse and rider.

The horse is on a slow trot, and is equipped with a Mexican bridle, curb-bit, a nicely embossed saddle and stirrups.

The rider leans slightly, his right arm thrown back holding his lasso coiled up, the end of which is fast-

ened to the pommel of the saddle; in his left hand he holds the reins, as may be seen in the photograph; on his heels are large-sized spurs; his legs are covered with buckskin breeches; a Mexican blanket or poncho (which is slipped over his head) loosely covers the upper portion of his body; his head-covering consists of a slouched hat.

I do not claim the design for the horse.

What I claim as my invention, and desire to secure by Letters Patent, is—

The design for the rider and the equipments of rider and horse, as above shown and described.

NICHOLAS MÜLLER.
